REFRIGERATOR FROST INDICATOR

Raymond E. Tobey, Springfield, Mass., assignor
to Westinghouse Electric Corporation, East
Pittsburgh, Pa., a corporation of Pennsylvania

Application July 12, 1946, Serial No. 683,277

7 Claims. (Cl. 62—1)

1

This invention relates to refrigeration apparatus and more especially to a means for giving an indication when an objectionable amount of frost has formed on the cooling unit of the apparatus.

It is an object of this invention to provide a novel and inexpensive frost indicator.

This and other objects are effected by the invention as will be apparent from the following description and claims taken in connection with the accompanying drawings, forming a part of this application, in which:

Fig. 1 is a view of the upper portion of the interior of a refrigerator cabinet embodying the frost indicator of this invention, the indicator indicating that defrosting is unnecessary;

Fig. 2 is a view similar to Fig. 1 but with the defrost indicator indicating that defrosting is necessary;

Fig. 3 is a sectional view substantially on the line III—III of Fig. 1, but with the door closed;

Fig. 4 is a view on the line IV—IV of Fig. 3;

Fig. 5 is a view similar to Fig. 4 but with the door open and showing the position of the indicator when defrosting is not necessary; and

Fig. 6 is a view similar to Fig. 5 but showing the position of the indicator when defrosting is necessary.

Referring to the drawings for a detailed description of the invention, the reference numeral 10 indicates a refrigerator cabinet comprising an outer metal shell 12, an inner liner 14, and heat-insulating material 16 interposed therebetween. A heat breaker strip 18 closes the space between the inner and the outer shell at the front of the cabinet 10, and a door 20 closes the access opening of the cabinet 10. A cooling unit 24, provided with refrigerant tubing 26, is located in the upper portion of the cabinet 10 and provides a storage space for frozen foods.

The defrost indicator of this invention comprises an electric light bulb 28 located in a dome-like indentation 30 in the upper wall 32 of the inner liner 14. A window 34 is provided in the upper wall of the cooling unit directly below the light bulb 28 so that the interior of the cooling unit is illuminated. An opening 36 is provided in the breaker strip 18 of the upper wall of the cabinet and opposite the light bulb 28. A window pane 38 carrying the legend "Defrost" is positioned adjacent the opening 36 and a housing 40 joins the opening 36 with a second opening 42 in the indentation 30 of the inner liner 14. The housing 40 provides a light shaft between the light bulb 28 and the window pane 38 so that when the door 20 of the refrigerator is opened and the light bulb 28 is lit, the legend "Defrost" is clearly visible.

2

A vertical shaft 44 is journaled near one side of the housing 40 and is retained at its upper end by a pin 46 riding on the housing 40. The lower end of the shaft 44 projects through the upper wall 32 of the inner liner 14 and carries a paddle wheel 48 which is located closely adjacent the refrigerant tubing 26 so that a heavy coating of frost accumulating on the cooling unit 24 will interfere with the rotation of the paddle wheel 48. A vane 50 is secured to the shaft 44 within the housing 40, and the shaft 44 and vane 50 are so located that by turning the shaft 44, the vane may be moved from a position in which it interrupts the light from the light bulb 28 through the housing 40 and in another position allows the light to pass through the housing 40 to illuminate the window 38. A spiral spring 52 is secured at one end to the shaft 44 and at the other end to the housing 40 and is stressed to rotate the shaft 44 to the position in which the vane 50 interrupts the light passing through the housing 40. A disc 54 is positioned between the spiral spring 52 and the vane 50 and carries an actuating arm 56. A push rod 58 projects through an opening in the breaker strip 18 of the upper wall of the cabinet 10 to be actuated by the door 20 when the door 20 is moved to the closed position. The other end of the push rod 58 is slidably secured in a support 60 within the housing 40 and contacts the actuating arm 56, the spiral spring 52 biasing the arm 56 against the inner end of the push rod 58.

A switch contact 62 is secured to the rod 58 and comprises an L-shaped member 64 of electrical insulating material secured to the rod 58 and carries a metallic bridging member 66 at its extremity. Two electrical contact points 68 are secured in the cabinet 10 that they are bridged by the bridging member 66 when the rod 58 moves to its extreme righthand position as viewed in Fig. 4. The contact points 68 lie in one of the electric supply lines 70 of the light bulb 28. A spiral spring 72 on the shaft 58 is interposed between the support 60 and the insulating member 64 to bias the rod 58 towards the front of the cabinet 10. The spiral spring 72 also biases the bridging member 66 against the contact points 68 when the door 20 is open, thus lighting the lamp 28.

The actuating arm 56 is so located with respect to the vane 50 and the push rod 58 that the push rod 58 moves the vane 50 out of the path of light between the lamp 28 and the window 38, when the door 20 is closed. When the door 20 is opened, the spiral spring 72 moves the push rod 58 to the right as viewed in Fig. 4, causes the electric light bulb 28 to light, and releases

the actuating arm 56 so that the vane 58 is moved by the spiral spring 52 to a position in which it interrupts the light from the bulb 28 to the window 38 provided there is not enough frost on the cooling unit 24 to engage the wheel 48. Under this condition, the legend "Defrost" will not be illuminated.

On the other hand, if the door is opened when a heavy layer of frost has formed on the cooling unit 24, the frost will prevent the rotation of the paddle wheel 48, and hence also the rotation of the shaft 44 so that the vane 58 does not interrupt the light from the bulb 28 to the window 38 and the legend "Defrost" is illuminated on the window 38. This is a signal for the user of the refrigerator that the cooling unit 24 requires defrosting.

The paddle wheel 48 is not fixedly secured to the shaft 44 but is merely in frictional engagement therewith sufficiently to prevent relative movement between the paddle wheel 48 and the shaft 44 under the bias of the spiral spring 52. This frictional engagement of the paddle wheel 48, however, allows the door 20 to be closed even though sufficient frost has accumulated on the cooling unit while the door 20 was open to engage the paddle wheel and hold it stationary. Under these conditions, slippage between the paddle wheel 48 and the shaft 44 occurs as the shaft 44 is forcibly turned by the actuating arm 56. This is a safety feature to prevent breakage of the indicator.

It will be apparent from the above that this invention provides a simple signaling device for a refrigerator cabinet which device indicates by the illumination of the legend "Defrost" that the frost accumulation on the cooling unit 24 is sufficiently heavy to require defrosting. This illumination is effected only when the door is opened.

While the invention has been shown in but one form, it will be obvious to those skilled in the art that it is not so limited, but is susceptible of various changes and modifications without departing from the spirit thereof.

What I claim is:

1. In a refrigerator cabinet having a food storage chamber, a cooling unit having a surface exposed to the air of said chamber, the combination with said surface of a member normally movable between a first position and a second position and in a direction substantially parallel to said surface, means for biasing said member from said first position to said second position, an actuating device responsive to said door for moving said member from said second position to said first position when said door is moved to its closed position, said device releasing said member for movement by said biasing means when said door is moved from said closed position, at least said first position of said member being closely adjacent said surface of the cooling unit so that frost forming thereon retains said member in said first position against the action of said biasing means when said door is moved from its closed position, and means for indicating whether said member is retained in said first position when said door is moved from said closed position.

2. The apparatus defined in claim 1 in which the normally movable member comprises a portion of a wheel.

3. The apparatus defined in claim 1 in which said last-named means interrupts a light beam when said normally movable member is in said second position.

4. In a refrigerator having a food storage chamber, a cooling unit having a surface exposed to the air of said chamber, an electric light bulb for illuminating the interior of said chamber, a door for said chamber, an object adapted to be illuminated by said light bulb, a shaft journaled for rotation, a vane on said shaft, said shaft being adapted for rotation between a first position in which said vane does not interrupt a light beam from said bulb to said object and a second position in which said vane interrupts said light beam, means for biasing said shaft from said first position to said second position, an operating member responsive to the movement of the door for moving said shaft from said second position to said first position when said door is moved to its closed position, and releasing said shaft for movement to said second position when said door is moved from its closed position, and a wheel frictionally retained on said shaft and positioned adjacent said surface to be engaged by frost forming thereon, said frictional engagement allowing slippage of said wheel on said shaft when said shaft is forcibly moved from its second position to its first position and said wheel is engaged by frost on said surface, said frictional engagement being sufficiently secure to prevent movement of said shaft from its first position to its second position when said wheel is engaged by frost on said surface.

5. The refrigerator defined in claim 4 in which said object is covered by said door when in the closed position and uncovered by said door when in said open position.

6. The refrigerator defined in claim 4 in which said operating member controls said light bulb to energize said bulb when said door is moved from its closed position and deenergize said light bulb when said door is moved to its closed position.

7. In a refrigerator cabinet having a food storage chamber, a cooling unit having a surface exposed to the air of said chamber, the combination with said surface of a shaft journaled for rotation, said shaft being rotatable between a first and a second position, means for biasing said shaft from said first to said second position, an actuating device responsive to said door for moving said shaft from said second position to said first position when said door is moved to its closed position, said device releasing said member for movement by said biasing means when said door is moved from said closed position, a wheel member on said shaft and in frictional engagement therewith, said frictional engagement being sufficient to prevent movement between said shaft and said wheel member by said biasing means but insufficient to prevent movement between said shaft and said wheel member by said actuating device, said wheel member lying adjacent said surface of the cooling unit so that frost formed on said surface prevents rotation of said wheel member, and means for indicating whether said shaft is retained in said first position when said door is moved from said closed position.
